UNITED STATES PATENT OFFICE.

MAURICE LACHMAN, OF NEW YORK, N. Y., ASSIGNOR TO UNIVERSAL ELECTRIC WELDING COMPANY, OF NEW YORK, N. Y., A CORPORATION OF NEW YORK.

FENCEPOST.

1,328,926.

Specification of Letters Patent.

Patented Jan. 27, 1920.

Application filed June 10, 1916. Serial No. 102,838.

To all whom it may concern:

Be it known that I, MAURICE LACHMAN, a citizen of the United States, and a resident of New York, in the county of New York and State of New York, have invented certain new and useful Improvements in Fenceposts, of which the following is a specification.

My present invention relates to the construction of skeleton metal posts or poles comprising intersecting members secured together.

The invention is particularly useful in the construction of fence posts owing to the simplicity and beauty of the structure when completed.

The object of the invention is to provide a simple, strong, ornamental, and at the same time, a cheap post for use in fences and for other purposes.

The invention consists in the improved post construction hereinafter more particularly described and then specified in the claims.

25 In the accompanying drawings, Figure 1 is a side elevation of a fence post constructed in accordance with this invention.

Fig. 2 is a transverse cross-section taken on the line 2—2 Fig. 1.

30 Fig. 3 is an enlarged front elevation of one of the upright members showing the manner of preparing the same at the point of intersection with a transverse member.

Fig. 4 is an enlarged front elevation showing one of the points of intersection between the upright and transverse members before applying the welding button.

Fig. 5 is an enlarged plan view of the welding button and Fig. 6 a central cross-section through the same.

Fig. 7 is a transverse section through one of the intersections between the members showing the completed joint, the section being taken on the line 7—7 Fig. 4.

45 In the drawings, 1 indicates the upright members preferably arranged parallel with each other and of which there may be any number desired while 2 indicates the transverse members any desired number of which are provided in spaced relation and arranged to intersect the upright members 1 at the desired intervals.

The uprights 1 are preferably T-shaped in cross-section while the members 2 are

plates of metal each provided with a central 55 opening 3. By preference the plates 2 are square in form although they may be of any desired shape in contour and the material thereof is of a thickness approximately equal to the thickness of the web portion of the 60 T-shaped uprights 1.

The uprights may engage the plates at any point about the periphery thereof but preferably are disposed at each corner, the corner for this purpose being squared off for 65 a distance equal to the width across the face of the flanges of the uprights 1 and provided with a slot to take the web of the upright as shown.

Certain portions of the flanges of the 70 members 1 at the points of intersection with the plates 2 are cut away as shown in Fig. 3 to leave a restricted mass 4 isolated from the flange and which is practically a bringing forward or exposing of the web of the 75 T. This is effected by forming openings 5 in the flanges at each side of the web of a length to leave a short portion of the web exposed at the point 4. By preference the openings 5 do not extend to the outer edges 80 of the flanges for the full length of the openings but only sufficient metal is removed at the edges of the flanges to provide openings 6 as wide as the thickness of the transverse plates 2 so that when the web of 85 the upright is inserted in the slot in the plate 2 the squared corner of the plate is permitted to be brought forward in the openings 6 until the edge is flush with the outer face of the upright members 1, the outer ends 7 90 of the flanges bearing on the opposite surfaces of the plates 2 as shown in Fig. 4 to prevent any tendency of the members to rock relative to each other. By this formation the squared corner or edge 8 of the plate 2 95 is brought into the same plane as the outer edge of the exposed web 4 and the intersecting edge 8 and exposed web 4 form a cross the arms of which are of equal thickness.

9 indicates a welding button preferably 100 in the form of a disk provided with an annular ridge 10 intermediate its edge. The ridge 10 is of such diameter that when the button is placed over the intersection of the members 1 and 2, the ridge will engage and 105 intersect the exposed web 4 and the squared edge 8 of the plate 2 as indicated by dotted lines in Fig. 4. The size of the button itself

is such that it will conceal the openings 5 in the member 1 and is preferably coextensive with the width of the flanges of the uprights 1. It will be understood that the 5 welding button 9 may be of any desired shape or contour for purposes of ornamentation.

The button 9 is placed over the intersection of the members 1 and 2 so that the ridge 10 intersects the parts 4 and 8 as previously 10 described. The points of intersection of the ridge with the parts 4 and 8 form isolated points of contact which allow the parts to be readily and quickly joined by the electric 15 welding process.

To electrically weld the button 9 to the members 1 and 2, the parts are held between the electrodes of a suitable electric welding machine and current is passed from one electrode to the other through the work at the 20 same time pressure being applied, preferably through the electrodes, to force the parts together and complete the weld. As the electric current passes from the members 25 1 and 2 to the button 9, the points of isolated contact formed by the intersections of the ridge 10, exposed web 4 and edge 8 soften and by the application of pressure coalesce with each other and form four points of 30 welded union at each joint, the points at which the welded unions take place being indicated at 11 in Fig. 4. It is thought that any further description of the electric welding action is unnecessary, the process being 35 now so well known and universally practised.

As indicated in Fig. 7 the slot formed in the plate 2 to take the web of the uprights 1 is preferably of less depth than the web 40 1 and the web is provided with a recess to allow for the short slot and to form shoulders 12 which engage opposite surfaces of

the plate 2 and lock the upright 1 against any tendency to longitudinal slippage.

It will be understood that the shape or 45 design of the post as well as its parts and the details of construction may be varied without departing from the spirit of the invention as expressed in the appended claims.

What I claim as my invention is:—

1. A metal post comprising T-shaped upright members, transverse plates intersecting said members at spaced intervals and having the web of said members seated in a recess thereof, the flanges of said members being removed at the intersection to expose the web and whereby the edge of the plate is brought into the same plane with the outer surface of the upright and a ridged button having the ridge thereof welded to the edge 60 of the plate and the exposed web of the upright to lock the members together.

2. A metal post comprising T-shaped upright members, transverse plates intersecting said members at spaced intervals and having the web of said members seated in a recess thereof, the flanges of said members being removed at the intersection to expose the web and whereby the edge of the plate is brought into the same plane with the outer surface of the upright and a ridged button having the ridge thereof welded to the edge of the plate and the exposed web of the upright to lock the members together, the outer edges of the flanges of the uprights engaging opposite surfaces of the plates.

Signed at New York, in the county of New York and State of New York, this 28th day of December, A. D. 1915.

MAURICE LACHMAN.
